UNITED STATES PATENT OFFICE.

CHARLES C. HUGHES, OF PHILADELPHIA, PENNSYLVANIA, ASSIGNOR TO HUGHES
UNIVERSAL ARC LAMP COMPANY, OF PHILADELPHIA, PENNSYLVANIA.

ARC-LAMP.

1,087,377.

Specification of Letters Patent. Patented Feb. 17, 1914.

Application filed August 31, 1911. Serial No. 647,068.

To all whom it may concern:

Be it known that I, CHARLES C. HUGHES, a citizen of the United States, residing at Philadelphia, State of Pennsylvania, have 5 invented certain new and useful Improvements in Arc-Lamps; and I do hereby declare the following to be a full, clear, and exact description of the invention, such as will enable others skilled in the art to which 10 it appertains to make and use the same.

This invention relates to certain novel and useful improvements in arc lamps and has particular application to lamps of the "hot wire" type.

15 In carrying out my invention it is my purpose to provide means whereby one of the carbons may be automatically adjusted relative to the other through the medium of a thermo-expansive wire with which it is 20 operatively connected.

It is also my purpose to provide a lamp of this type in which the friction of the operating parts is reduced to a minimum and such parts are so correlated and arranged as to 25 work positively and efficiently under all conditions.

I also aim to provide a lamp which will embody the desired features of simplicity and reliability.

30 With the above recited objects and others of a similar nature in view, my invention consists in the construction, combination and arrangement of parts set forth in and falling within the scope of the appended claims.

35 Figure 1 is a view in side elevation of my improved lamp, certain of the parts being shown in section. Fig. 2 is an enlarged view of the lamp, taken partly in vertical section and partly in elevation, the lower portion of 40 the lamp being broken away. Fig. 3 is a horizontal sectional view taken on line 3—3 of Fig. 1. Fig. 4 is a sectional view taken on the line 4—4 of Fig. 1. Fig. 5 is a sectional view taken on the line 5—5 of Fig. 1. Fig. 6 45 is a sectional view taken on the line 6—6 of Fig. 8. Fig. 7 is a sectional view taken on the line 7—7 of Fig. 2. Fig. 8 is a sectional view taken on the line 8—8 of Fig. 2. Fig. 9 is a sectional view taken on the line 9—9 of 50 Fig. 6, and Fig. 10 is a sectional view taken on the line 10—10 of Fig. 7.

Referring now to the accompanying drawings, in detail, the numeral 10 indicates my improved lamp as an entirety. This lamp is 55 provided with the upper and lower plates

11 and 12 respectively which are connected by means of the vertical standards 13, the opposite ends of which are reduced and threaded as at 14 to extend through reinforcing insulating sleeves 15 located in 60 apertures 16 in the plates 11 and 12. The lower plate 12 has secured to its under face by means of suitable fastenings 17, a depending bracket 18 which is provided with an annular flange 19 into which the fastenings 17 extend.

The numeral 20 indicates a plate located at the under side of the bracket 18 and held in spaced relation therefrom by the interposed insulating disk 21. Through the 70 alining apertures 23 of the bracket and insulating plate and base plate respectively extend insulating sleeves 22 for the purpose hereinafter described. The annular flange 19 is provided at opposite sides with threaded apertures 25 for the reception of set screws 26 to which latter are connected the upper ends of retractile springs 27, the lower ends of said springs being secured to the upper ends of the globe supporting bracket 28. 80

The lower carbon of the lamp is shown at 29 and is designed to seat in the socket 30 formed by flanges carried by the plate 31. This plate 31 is provided with vertical supporting rods 32 extending at their upper 85 ends through the sleeves 22 and provided with adjustable nuts 33 for holding the carbon socket against displacement. Extending through the opening 34 in the plate 12 is a binding post 35 which engages with the 90 contact plate 36 carried by the adjacent supporting rod 32. A flexible conducting insulating wire 37 is connected at one terminal to this binding post 35 and extends to the upper plate 11, to which it is connected by 95 means of the binding post 38. From this post it extends through a central aperture 39 formed in the plate 11 and is attached to the plug 40 supported by the hood 41, which hood is held in spaced relation to the plate 100 11 by the supporting bolts 32'. It is, of course, to be understood that the plugs 40 are designed to be connected with any suitable source of current supply.

The binding post 38 is connected with a 105 plate 42, which latter is provided with ears 43 carrying the pivoted bar 44 which is adjustable by means of a set screw 45 threaded through one end of the bar 44 and adapted to contact with the plate 42. At the oppo- 110

site end of the bar 44 from the binding post 38 is a spring clip 46 holding the thermo-expansive wire 47 which passes downwardly over the pulley 48 carried by the bracket 49 5 on the adjacent standard 13, said wire passing thence upwardly over the spaced pulleys 50 carried by the brackets 51 attached to the under side of the top plate 11. The wire thence passes downwardly under the pulley 52 carried by the pivoted clevis 53 and thence upwardly to the binding post 54 supported by the bracket 55 which depends from the lower side of the upper plate 11 from which it is held against contact by a 15 strip of insulating material 56. The wire 47 is held in contact with the depending extension of the bracket 55 by means of the spring clip 57. A binding post 58 is attached to the bracket 55 and has secured thereto one terminal of the artificial resistance 59 which surrounds one of the guide rods 60 attached to the plates 11 and 12 for the purpose hereinafter described.

The upper carbon is shown at 61 and is 25 designed to be received by the sleeve 62. This sleeve is provided with spaced parallel plates 63 in the ends of which are journaled guide rollers 64 designed to bear against and slide upon the spaced parallel guide rods 60. 30 One of the plates 63 carries a set screw 65 to which is connected an end of the coiled portion of the artificial resistance 59.

The numeral 70 indicates a plate mounted on one of the standards 15 and offset as at 35 71, to receive the adjustable pin 72 which is retained in position by the locking nut 73. The lower end of the pin 72 has connected thereto the upper end of the retractile spring 74, the lower end of the latter being 40 designed to engage in one of the series of notches 75 formed in the under side of the arm 76 pivoted at 77 to the standard 13 carrying the plate 70. The before-mentioned clevis 53 is pivoted at its lower end 45 to the short extension of the lever 76. The opposite or inner end of this lever is provided with an interiorly threaded opening 78 for the reception of the operating bolt 79. As will be seen by reference to Fig. 9, 50 the end face of the lever and the adjacent face of the bolt 79 are formed to produce parallel shoulders 80, while 81 indicates a roller rotatably mounted upon the bolt 79. This roller is grooved as at 82 at opposite 55 ends to produce ball races for the ball bearings 83 which form anti-friction means so that the roller may move readily upon its bearings. This roller 81 is designed to bear against and operate the clutch member 84 of 60 the upper carbon, as will be hereinafter described. This clutch member 84 is best shown in Figs. 6 and 8 and comprises a sleeve block 85 slidable upon the lower portion of the upper carbon 61 and is provided 65 with oppositely disposed pairs of extensions

86 and 87. These latter are each formed with longitudinal notches 88. For the reception at the ends of the axles 89, each axle is formed with flanges 90 to contact with the adjacent sides of the extensions 86 and 87. Grooved rollers 91 are rotatably mounted upon the axles 89 and are formed at their ends with ball races 92 in which are located ball bearings 93 for engagement with the axle 89, the flanges 90 and the rollers 91 thereby lessening the friction upon the vertical movement of the clutch member 84. A guide plate 94 is secured to the block 85 and is provided with opposite ends 95 to engage the outer sides of the guide rod 60 thereby maintaining the clutch member 84 against accidental displacement. The block 85 is further formed with a slot 96 at the sides of which are ears 97.

98 indicates a cam lever which is pivoted between the ears and is adapted to bear at its inner end against the carbon. The outer portion of the lever is constructed similar to the inner or free end of the lever 76, that is to say, is provided with a threaded socket 99 in which is located a bearing bolt 100. On this bolt is journaled a roller 101, formed with a ball race 102 to receive ball bearings 103 for lessening the friction between the roller and the members whereby it is supported. This roller is designed to extend transversely across and rest upon the roller 81 causing the cam lever to engage and release the carbon upon the operation of the lever 76 caused by the expansion and contraction of the thermo-expansive wire 47. A bracket 104 is secured to the upper side of the lower plate 12 in the path of the clutch 84 and limits the downward movement of the latter. A conductor wire 105 is attached to one of the plugs 40 and to the upper carbon 61, as shown at 106 for the purpose of completing the circuit and supplying the current.

I wish now to call attention to the rollers 110 48, 50 and 52. These are preferably made of porcelain and the supporting members therefor are each formed of two sections 107 and 108, the upper ends of which are stamped outwardly to produce ball races 109 115 in which are located ball bearings 110. Axles 111 are provided for the rollers, the balls bearing upon the axles and against the sides of the roller. In order to prevent the rollers from cracking, as is liable to be 120 caused by the expansion and contraction of the wire 47 due to the heating and cooling of the latter, these rollers 48, 50 and 52 are formed with openings slightly greater than the diameters of the axles 111, which openings are provided with longitudinal corrugated bushings 112 which will permit the necessary expansion and contraction. A plate 113 is secured to the lower plate 12 125 and is formed with a vertically extending 130

T-shaped projection 114 which has connected to the opposite ends of its head 115 coil springs 117 which are in turn connected as indicated by the numeral 118. These coil springs form the ordinary electrical resistance for the lamp.

In order to suspend or hang the lamp any suitable means for this purpose may be connected with a convenient part of the lamp, 10 such for instance, as the hood.

When the lamp is properly arranged for lighting purposes and the current is turned on to pass through the carbons in the usual manner, the thermo-expansive or hot wire 15 practically simultaneously becomes heated and expands. This lengthening of the wire allows the short end of the lever 76 to move downward, this downward movement being assisted by the action of the retractile spring

20 74, which, pulling upward moves the roller 81 into engagement with the roller 101, thus raising the lever 98 and throwing the cam end of the latter into engagement with the upper carbon 61, raising the latter from engagement with the lower carbon 29 by the further contraction of the spring 74. As the distance between the carbons increases the current passing through the wire 47 will be constantly diminished, thus permitting 25 the wire to cool sufficiently to cause its contraction and allowing of the upper movement of the short end of the lever 76. This upper movement of the lever 76 releases the lever 98 from its engagement with the upper carbon 61, releasing the latter and allowing it to return to its initial position in contact with the lower carbon 29. The operation 30 will then be repeated as previously described.

It will be seen that by means of my lamp

the upper carbon will be properly and gradually fed through the sleeve of the clutch member as the carbon is consumed, thus always maintaining the two carbons in proper position to produce uniform light.

What I claim is:

1. In an arc lamp, the combination with 45 fixed and movable carbons, of a continuous length of expansible circuitously arranged wire in an electric circuit with the carbons, means at different points of the length of the 50 circuitous wire for supporting it and for permitting instant and uniform expansion thereof throughout the successive portions of its length under the influence of a current of varying intensity, and mechanism controlled 55 by the expansion and contraction of the wire for varying the correlative position of the carbons.

2. In an arc lamp, the combination with 60 two carbons, of a continuous length of expansible wire arranged in circuit with the carbon, supporting members for the wire at different points of its length, constructed and arranged to permit the uniform and instant expansion of such wire through the 65 successive portions of its length under the influence of a current of varying intensity, and clutch mechanism engaging with one of said carbons and controlled by the contraction and expansion of the wire, for varying 70 the position of such carbon relative to the other carbon.

In testimony whereof, I affix my signature, in presence of two witnesses.

CHARLES C. HUGHES.
